CLAIM

We claim the ornamental design for a removable support mount, as shown and described.

DESCRIPTION

FIG. 1 is a top perspective view of a removable support mount in accordance with our new design;

FIG. 2 is a bottom perspective view of the removable support mount of FIG. 1;

FIG. 3 is a top view of the removable support mount of FIGS. 1-2;

FIG. 4 is a bottom view of the removable support mount of FIGS. 1-3;

FIG. 5 is a left-side elevation view of the removable support mount of FIGS. 1-4;

FIG. 6 is a right-side elevation view of the removable support mount of FIGS. 1-5;

FIG. 7 is a front elevation view of the removable support mount of FIGS. 1-6; and,

FIG. 8 is a rear elevation view of the removable support mount of FIGS. 1-7.

The broken lines in the drawings illustrate portions of the removable support mount that form no part of the claimed design.
